15 Claims. (Cl. 179—18)

It is usual for the signals which in telephone installations indicate to the calling subscriber the condition of the desired line, to be transmitted back from that selector stage up to which the connection has been made. Thus, the so-called "selecting" or "dialling" signal which indicates to the subscriber that he has been connected to a free numerical current impulse receiver and can begin emitting selecting current impulses is usually transmitted from the calling subscriber's feed circuit. The "busy" signals which are transmitted when all outlets from a selector are busy are evolved in the selector which is unable to find a free outlet. The "ringing" signal which indicates that the desired subscriber's line is idle is transmitted from the final selector. An arrangement has already been proposed with which, if the called subscriber is engaged, the connecting devices are automatically released up to the first group selector; it has also been proposed to use an intercepting circuit and to extend the release as far as the calling subscriber's individual relays. In these cases, the "busy" signal would be transmitted from the first group selector or the subscriber's individual relays. The "ringing" signal would also be transmitted always from the final selector.

The object of the invention is to simplify the transmission of these signals. With this end in view, in accordance with the invention, the devices provided for giving the various signals are arranged in the calling subscriber's exchange and are controlled from the distant exchanges. With this arrangement, the signal transmitting devices are preferably associated with the calling subscriber's feed circuit. By uniting all the signal transmission devices at one and the same place, it can be arranged that the calling subscriber always receives the signals at the same rhythm and the same pitch. These signals, moreover, will not be excessively weakened or damped. A particularly marked improvement is thus effected in cases in which connections are made through a number of exchanges connected by lengthy lines. It is usual for the "ringing" signals transmitted by the last selector stage of the terminal exchange to be transmitted to the calling subscriber over a lengthy line so that they are frequently received in a very weakened state. In telephone installations in which amplifiers are used, the amplifiers have been used for strengthening the signals. This, however, requires the use of special balancing devices because the amplifiers when connected to a line which has not yet been connected through to the desired sub-

scriber readily tend to oscillate. All these special devices can be avoided in accordance with the invention as the speech amplifier only has to be connected after the called subscriber has replied, that is to say, after the connection has been made to the desired line.

One embodiment of the invention is shown in the accompanying drawing in which:

Figure 1 shows diagrammatically the circuits of a call finder and a group selector.

Figure 2 shows the circuits of an inductively coupled line and the transmitters associated therewith, and

Figure 3 shows the circuit of a final selector. 15 It will first of all be assumed that the group selector shown in Figure 1 is directly connected to the final selector shown in Figure 3 and that the line shown in Figure 2 has not yet been connected.

- 20 When the subscriber TN lifts his receiver, a "multi-step" relay T is energised through its winding I in the first stage. The contacts t_1 and t_2 are thus closed and a call finder AS is thus brought into operation. When the call finder 25 finds a free outlet, the relay C responds (winding I), the relay T (winding II) is energised in the second stage and opens the calling circuit at the contacts t_3 and t_4 . By means of its contacts c_1 and c_2 the relay C connects the speech lines so that the windings I of the feed 30 circuit relays A and B are energised. The calling subscriber now receives the "dialling" signal which is transmitted through the contact g_k (closed in the normal position of the group selector) to the windings II of the relays A and B from a signal transmitter connected to the terminal s_1 . The numerical current impulses transmitted by the subscriber are received in the usual manner by the relay A and are used for setting 35 the group selector. A slow-to-release relay V is energised through the contact a_1 during each train of current impulses and releases at the end of each train. When the group selector finds a free line to a final selector, the relay P responds 40 and by means of its contacts p_1 and p_2 connects through the speech lines. The relay $4G$ in the final selector (Fig. 3) is thus energized. The next current impulses are transmitted by means of a contact a_2 through one speech wire to the final selector and are received there by the relay 45 $4A$ which in known manner sets the final selector. The slow-to-release relay $4V$ is kept energised by the contact $4a$ during each train of current impulses and releases at the end of each 50 train. During the second setting movement of 55

the final selector the wiper shaft of the selector mechanically closes a contact *wk* so that a circuit is prepared for a relay 4R. A relay 4U is energised from the beginning of the energisation of the final selector. When the relay 4V drops at the end of the second train of current impulses acting on the final selector, the circuit for the testing relay 4P and also the circuit for the relay 4R are closed. The relay 4R responds, opens the circuit for the slow-to-release relay 4U at its contact 4r so that the relay 4U releases and itself opens the circuit for the testing relay 4P at its contact 4u. The delay in release of the relay 4U thus limits the testing time.

If the called subscriber's line is busy, the relay 4P cannot respond during the testing time. On release of the relay 4U, the b-wire of the speech line is connected through the resistance W1 to the negative side of the source of current. In the group selector (Figure 1) the relays Fr and M are connected to the b-wire of the speech line. The relay Fr is non-sensitive and can only respond to a strong current, while the relay M is sensitive enough to respond to weak currents. The resistance W1 is so great that the current which flows over the b-wire of the speech line is so weak that only the relay M is actuated. The contact *m1* connects up the "busy" signal transmitter connected to the terminal *s2* and the "busy" signal is transmitted inductively to the calling subscriber over the windings II of the relays A and B. If it is desired that in the case of the desired line being engaged, the connection should be released up to the calling subscriber's individual relays, the relay M is provided with a further contact *m2* which short circuits the winding II of the relay C and thus causes the relay C to release. When the relay C releases, the circuit for the winding II of the subscriber's relay T is also interrupted. The subscriber's individual relays include a relay R, the winding I of which was energized through the contact *t5* after the testing by the call finder so that the relay reverses its contacts. If now the energising circuit of the relay T is opened, this relay first restores the contacts actuated in the second stage into the normal position. When the contacts *t3* and *t4* close, a circuit is closed through the winding I of the relay T and the winding II of the relay R. In this circuit, the relay T is held energised in the first stage and the relay R is also held energised. The "busy" signal transmitter is now connected to the winding III of the relay T by the contacts *r3* and *t1* and the signal is transmitted inductively to the calling subscriber. The relays remain energised until the subscriber replaces his receiver. The group selector is restored into the normal position in the known manner on release of the relay C.

If the line seized by the final selector is free, the relay 4P responds on closing of the testing circuit. The b-wire of the speech line is connected over the contacts 4u3 and 4p4 and the resistance W2 to the negative side of the source of current for the duration of the delay in release of the relay 4U. The resistance W2 is considerably smaller than the resistance W1. Owing to the considerably stronger flow of current through the b-wire of the speech line in the group selector, both the relay M and the relay Fr (winding I) are energised. The relay Fr responds by means of its contact *fr1*, closes a holding current through its winding II and by reversing its contact *fr2* makes the busy signal transmitter connected to the terminal *s2* inoperative. At the same time, the

"free" signal transmitter connected to the terminal *s3* is connected up. The contact *fr3* connects the winding I of a two-step relay Z to the b-wire of the speech line. This relay, however, cannot respond because it is short circuited over the resistance W2 of the final selector.

The delay in the release of the relay 4U is approximately 100 milliseconds. When the relay 4U drops, the connection of the resistance W2 with the b-wire of the speech line is broken at the contact 4u3. The short circuit for the winding I of the relay Z is thus removed and the relay Z is energised in the first stage through the relays M and Fr and reverses its contacts *z11*, *z12*, and *z13*. The contact *z11* connects one end of the winding I of the relay Z preparatorily to the positive side of the source of current. The contact *z12* closes a holding current through the winding II of the relay Z while the contact *z13* makes the "free" signal transmitter connected to the terminal *s3* inoperative, and in its place connects up the periodic "free" signal transmitter connected to the terminal *s4*. If the line is free, the subscriber therefore receives first a short "free" signal for the duration of the delay in response of the relay 4U of the final selector and then a periodic "free" signal corresponding to the periodic call transmitted to the desired subscriber in the final selector. This periodic "free" signal transmitter may be connected in known manner to the periodic call device of the exchange in question.

The transmission of the periodic call in the final selector is not shown in the circuit. When the desired subscriber replies, the relay 4Y responds and by means of the contact *4y*, connects the b-wire of the speech line to the negative side of the source of current over the resistance W2. As the winding I of the relay Z is now connected to the positive side by the contact *11*, the relay Z is energised in the second stage by the current flowing over the b-wire. The contact *zs1* now cuts out the relay M and the winding I of the relay Dr. The contact *zs2* closes a holding current through the winding II of the relay Z. The contact *zs3* also disconnects the winding I of the relay Z from the speech line and the contact *zs4* interrupts the periodic "free" signal. At the same time, the contact *zs5* prepares the metering which is carried out in the known manner when the calling subscriber replaces his receiver and the relay C in consequence releases.

As may be seen, all signals are thus given from the calling subscriber's feed circuit. For the "busy" signal, a weak flow of current through the b-wire of the speech line is used and for the "free" signal, a short strong flow of current is used which, at the beginning, switches in the "free" signal transmitter and at the end switches over to a periodic "free" signal transmitter. When the called subscriber replies, the "free" signal is switched off by a second strong flow of current through the b-wire of the speech line, and the metering operation is put into operation.

If a "busy" signal is to be given should a group selector not find a free line, it is only necessary to connect the b-wire in the selector stage in question to the negative side of the source of current over a great resistance. In the group selector shown, the relay M can be locally energised through a second winding on a contact closed by the selector running over its contact bank.

If the connection is made through inductively coupled trunk lines, the operation performed for the signal transmission must result in the trans-

mission of alternating current impulses through the trunk line. An arrangement of this kind is shown in Figure 2. The outgoing transmitter U_1 is seized by the group selector of Figure 1 so that the relay $2C$ responds. The relay $2A$ is energised through the contacts $2c_2$ and $2u$ for the duration of the delay in response of the relay $2V$ and through its contacts $2a_1$ and $2a_2$ transmits an alternating current impulse. This impulse is received in the incoming transmitter U_2 by a relay $3A$ which energises the seizing relay $3C$. The latter holds itself energised and with its contact $3c_2$ energises the relay $4C$ of the final selector. The current impulses which are sent out by the subscriber and transmitted by the relay A of the group selector (Figure 1) are converted by the relay $2A$ of the transmitter U_1 into alternating current impulses and transmitted by the relay $3A$ of the transmitter U_2 through the a -wire of the speech line as direct current impulses. If the desired subscriber's line is busy, the b -wire is connected in the final selector (Figure 3) to the negative side of the source of current over the resistance W_1 and a sensitive relay $3M$ responds in the incoming transmitter U_2 . The relay K however does not respond to the weak current. By means of its contact $3m_1$, the relay $3M$ energises the relay $3S$ and the latter, with its contacts $3s_1$ and $3s_2$, sends back alternating current through the trunk line. The circuit of the relay $3S$ passes through the contact $3n$ of the relay $3N$ which has been preparatorily energised from the beginning of the seizing of the incoming transmitter. This relay $3N$ is short circuited by the contact $3m_2$ so that the energisation of the relay $2S$ and the transmission of the alternating current is limited to the duration of the delay in release of the relay $3N$. The alternating current is received in the outgoing transmitter by the relay $2W$ which, with its contact $2w$ causes energisation of a relay Y and at the same time short circuits the relay $2N$ which has been energised from the beginning of the seizing of the outgoing transmitter. The delay in release of the relay $2N$ is shorter than that of the relay $3N$ which determines the duration of the alternating current transmission. The relay $2N$ thus drops during the received long alternating current impulse. At the end of the alternating current impulse the relay X in addition to the relay Y is energised over its winding I on release of the relay $2W$. The contact x_1 now connects the b -wire of the speech line to the negative side of the source of current over the contact $2n$ and the resistance W_3 . The resistance W_3 , just like the resistance W_1 of the final selector, is of such dimensions that the weak current flowing over the b -wire can only energise the relay M of the group selector. The relay M of the group selector then switches in the "busy" signal transmitter in the manner already described and causes the connection to be released.

If the desired subscriber is free, then the b -wire of the speech line is connected to the negative side of the source of current over the resistance W_2 for the delay in release of the relay $4U$. The strong current which is thus caused to flow through the b -wire energises both the relay $3M$ and the relay K (winding I). The relay K , by means of its contact k_1 , closes the circuit for the relay $3S$ and at the same time by means of its contact k_2 energises a relay L which, by means of its contact l_1 , re-opens the circuit for the relay $3S$. The relay L is slow-to-attract so that the relay $3S$ is energised for the duration of the

delay in attraction and sends back alternating current through the trunk line. By reversal of the contact k_1 , the contact $3m_1$ of the relay $3M$ is made inoperative. The contact k_3 of the relay K maintains the connection between the winding I of the relay K and the b -wire of the speech line after the response of the relay L so that the relay K does not drop until the flow of current through the b -wire ceases. By means of its contact k_1 , the relay K for the duration of the delay in the response of the relay L again closes a circuit for the relay $3S$ which for the second time transmits a short alternating current impulse. On response of the relay K , a two-step relay O (winding I) is energised in the first stage over the contact k_4 and by means of its contact o_1 prepares the energising circuit for its winding II . When the relay K releases, this circuit is closed so that the relay O responds in the second stage, closes a holding circuit for itself by means of its contact o_3 and, by means of its contact o_2 , prepares the energisation of the relay T . The temporary strong flow of current through the b -wire thus causes the transmission of two alternating current impulses through the trunk line.

At the outgoing transmitter, the relay Y is energized at the beginning of the first alternating current impulse and, by means of its contact y , prepares the circuit for the winding I of the relay X . At the end of the first current impulse, the relay X is energised in addition to the relay Y . The contact x_1 is thus closed and the b -wire is now connected to the negative side of the source of current over the resistance W_4 (the relay $2N$ has not released owing to the shortness of the alternating current impulse received). The resistance W_4 , just like the resistance W_2 of the final selector LW , is so dimensioned that a strong current flows over the b -wire. Consequently, the relay Fr in the group selector is energised and switches in the "free" signal transmitter in the manner already described.

At the beginning of the second alternating current impulse, the energising circuit for the relay Y is interrupted but the relay X is kept energised by way of its winding II . It is not until at the end of the second alternating current impulse that the relay X also drops and interrupts the flow of current through the b -wire of the speech line. On termination of the flow of direct current through the b -wire of the speech line, in the manner already described, the relay Z in the group selector is energised in the first stage by way of its winding I and switches in the periodic "free" signal transmitter (terminal s_4) instead of the "free" signal.

If, now, when the subscriber replies, the relay $4Y$ of the final selector is energised and the contact $4y$ causes the b -wire of the speech line to be connected to the negative side of the source of current over the resistance W_2 , the relay K in the incoming transmitter U_2 responds and seizes the relay L so that the relay $3S$ is energised for the duration of the delay in attraction of the relay L and transmits alternating current to the trunk line. At the same time, the relay T is energised by the contact k_4 and by means of its contact t removes the short circuit for the relay $3N$ so that this relay is positively prevented from releasing.

The short alternating current impulse which is sent back over the trunk line again first causes the relay Y to be energised and then the relay X of the outgoing transmitter U_1 . The contact x_1 again connects the resistance W_4 to

the b-wire of the speech line so that a strong direct current flows over the b-wire which, in the manner already described, energises the relay Z of the group selector in the second stage. The contact zs4 disconnects the "free" signal transmitter and the contact zs5 starts the metering procedure.

The weak direct current flowing through the b-wire of the speech line which is transmitted when the "busy" signal is given is thus converted at the incoming transmitter into a long alternating current impulse which is in turn converted in the outgoing transmitter to a weak direct current. The first strong direct current flow which is transmitted from the final selector when the indication is given that the desired subscriber's line is idle is converted into two short alternating current impulses which are reconverted in the outgoing transmitter into a strong direct current flowing for a limited time. The second strong direct current impulse which is transmitted when the desired subscriber removes his receiver is reconverted in the incoming transmitter into a short alternating current impulse which in turn is converted back in the outgoing transmitter into a strong direct current. This conversion into alternating current impulses which are transmitted through the inductively coupled trunk lines can naturally be repeated a number of times at various points in a connection if a number of trunk lines are seized. If amplifiers are provided for the amplification of the speech current, they are not seized until the subscriber replies and thus actuates the switch means associated with the transmitters, for example, the relay T in the incoming transmitter U2 so that the amplifiers are only brought in when the speech line has been completely connected.

I claim:

1. A multi-exchange automatic telephone system in which audible signals are automatically transmitted to a calling subscriber to indicate to him whether the line to which he desires to be connected is idle or busy comprising means at the called exchange for transmitting back to the calling exchange different signals according as the desired line is idle or busy, means at the calling exchange for transmitting the desired audible signals to the calling subscriber, means at the calling exchange for bringing said last-mentioned transmitting means into operation on receipt of said signals from the called exchange and means at the calling exchange actuated on receipt from the called exchange of a signal indicating that the desired line is busy for releasing the connection made by the calling subscriber.

2. A multi-exchange automatic telephone system in which audible signals are automatically transmitted to a calling subscriber to indicate to him whether the line to which he desires to be connected is idle or busy comprising means at the called exchange for transmitting back to the calling exchange a relatively weak current over one of the wires of the speech line when the desired line is busy and a relatively strong current of predetermined length over the same wire when the desired line is idle, means at the calling exchange responsive to said relatively weak current for transmitting the desired audible busy signal to the calling subscriber, and means at the calling exchange responsive to said relatively strong current for transmitting

the desired audible idle signal to the calling subscriber.

3. A multi-exchange automatic telephone system as claimed in claim 2, in which said last-mentioned means comprise means for transmitting a continuous audible signal to the calling subscriber during the flow of said relatively strong current and means for transmitting an intermittent audible signal when said flow ceases.

4. A multi-exchange automatic telephone system as claimed in claim 2 in which said last-mentioned means comprise means for transmitting a continuous audible signal to the calling subscriber during the flow of said relatively strong current and means for transmitting an intermittent audible signal when said flow ceases and comprising means at the called exchange arranged, when the called subscriber hangs up, to transmit a relatively strong current over said wire of the speech line and means at the calling exchange responsive to said last-mentioned current for interrupting the transmission of the audible idle signal.

5. A multi-exchange automatic telephone system in which audible signals are automatically transmitted to a calling subscriber to indicate to him whether the line to which he desires to be connected is idle or busy comprising a plurality of exchanges connected by trunk lines having an inductive transformer at each end, means at the called exchange for transmitting back a relatively weak current over one of the wires of the speech line when the desired line is busy and a relatively strong current over the said wire when the desired line is idle, means associated with the transformer at the called exchange responsive to said weak and strong currents for converting them into alternating current impulses of different length, means associated with the transformer at the calling exchange responsive to said alternating current impulses for converting them back to weak and strong currents and transmitting them over the wire of the speech line at the calling exchange corresponding to the wire of the speech line at the called exchange over which said first-mentioned weak and strong currents were transmitted and means at the calling exchange responsive to said last-mentioned weak and strong currents for transmitting the desired audible signals to the calling subscriber.

6. In a telephone system, an automatic exchange, a plurality of subscribers' lines terminating at said exchange, automatic switches in said exchange differently operated according as a called subscriber's line is busy or idle, a further automatic exchange, a plurality of subscribers' lines terminating at said exchange, means associated to said further exchange for transmitting different audible signals to a calling subscriber's line terminating at said exchange, a trunk line connecting said exchanges and means in said further exchange controlled by said automatic switches over said trunk line for bringing into operation said signal transmitting means according as said called subscriber's line is busy or idle.

7. In a telephone system, an automatic exchange, a plurality of subscriber's lines terminating at said exchange, automatic switches in said exchange differently operated according as a called subscriber's line is busy or idle, a further automatic exchange, a plurality of subscriber's lines terminating at said exchange, a trunk line connecting said exchanges, and means in said further exchange controlled by said automatic

switches over said trunk line for transmitting a busy tone or a ringing tone over a calling subscriber's line according as said called subscriber's line is busy or idle.

8. In a telephone system at least one calling subscriber's line, at least one feed circuit connected to said line, at least one connector, at least one called subscriber's line seizable by said connector, automatic selectors for connecting said feed circuit to said connector, switch means associated with said connector and differently operated according as said calling subscriber's line is busy or idle, and means associated with said feed circuit and controlled by said switch means for transmitting a ringing tone over said calling subscriber's line if said called subscriber's line is free.

9. In a telephone system a called connector, at least one calling subscriber's line seizable by said connector, automatic switches associated with said connector and differently operated according as said subscriber's line is busy or idle, means for transmitting ringing current to said called subscriber's line controlled by said automatic switches, a feed circuit, at least one calling subscriber's line connected to said feed circuit, at least one selector connecting said feed circuit to said connector, and means associated with said feed circuit and controlled by said automatic switches for transmitting an intermittent signal current over said calling subscriber's line if said called subscriber's line is free.

10. In a telephone system, an automatic exchange having a plurality of connectors, a plurality of subscribers' lines terminating at said exchange and connected to the fixed contacts of said connectors, automatic switches differently operated according as a desired subscriber's line is busy or idle, means controlled by said automatic switches for transmitting ringing current over an idle desired subscriber's line, a further automatic exchange, a plurality of subscriber's lines terminating at said further exchange, a trunk line connecting said exchanges and means in said further exchange controlled by said automatic switches over said trunk line for transmitting a ringing tone over a calling subscriber's line if said desired subscriber's line is idle.

11. An automatic telephone system comprising a plurality of exchanges, trunk lines connecting said exchanges, a plurality of subscriber's sets having impulse transmitting devices, a subscriber's line connecting each of said subscribers' sets to one of said exchanges, an impulse controlled connector switch at each of said exchanges, test means associated individually with said connector switches for testing a called subscriber's line, time switching means for making said test means effective during a predetermined time after the setting of said connector switches, means arranged at each of said exchanges for transmitting different audible signals to a calling subscriber connected to the same exchange to indicate whether a called subscriber's line is idle or busy, backward signal transmitting means arranged at each exchange, backward signal re-

ceiving means arranged at each exchange for bringing said audible signal transmitting means into operation in accordance with the nature of the received signal, and means associated with 5 said connector switches for controlling the backward signal transmitting means at the same exchange, said last mentioned means being controlled by said test means and by said time switching means for the transmission of a direct current impulse of predetermined length to said backward signal transmitting means when a called subscriber's line is idle.

12. An automatic telephone system comprising a plurality of exchanges having selectors controlled by current impulses, trunk lines connecting said exchanges, a plurality of subscribers' sets having impulse transmitting devices and connected by subscriber's lines to said exchanges, means associated with a called exchange for transmitting a backward signal when a called subscriber's line is idle and a different backward signal when the called subscriber removes his receiver, means associated with a calling exchange for transmitting different audible signals to the calling subscriber indicating whether a called subscriber's line is idle or busy, means at said calling exchange for receiving said backward signals and for bringing said audible signal transmitting means into operation in accordance with the nature of the received backward signal, said audible signal transmitting means being adapted to transmit on receipt of said first mentioned backward signal first of all a continuous signal and then an intermittent signal.

13. An automatic telephone system according to claim 12, in which said backward signal receiving means are adapted to stop the transmission of said intermittent signal on receipt of the backward signal indicating that the called subscriber has removed his receiver.

14. An automatic telephone system, comprising a plurality of exchanges, trunk lines inductively coupled to said exchanges, a plurality of subscriber's sets connected by subscriber's lines to said exchanges, means arranged at a calling exchange for transmitting to the calling subscriber different audible signal currents indicating whether a called subscriber's line is idle or busy, means associated with a trunk line and arranged in the called exchange for transmitting backward signals by alternating current impulses when the called subscriber's line is idle and also when the called subscriber removes his receiver and backward signal receiving means associated with said trunk line and arranged at the calling exchange and adapted, on receipt of said backward signal to bring said audible signal transmitting means into and out of operation.

15. An automatic telephone system according to claim 14, comprising also means arranged at the calling exchange for preparing the metering operation, said means being controlled by said backward signal receiving means on receipt of a backward signal indicating that the called subscriber has removed his receiver.

MARTIN HEBEL.
